United States Patent Office

Des. 221,871
Patented Sept. 14, 1971

221,871

SADDLE RACK

Woodrow W. Pearce, 1200 Riverside Drive,
Burbank, Calif. 91506

Filed Nov. 24, 1969, Ser. No. 20,241

Term of patent 14 years

Int. Cl. D30—99

U.S. Cl. D30—45

FIG. 4.

FIG. 1.

FIG. 3.

FIG. 1 is a front elevational view of a saddle rack embodying my new design;

FIG. 2 is a side elevational view thereof;

FIG. 3 is a top plan view thereof; and

FIG. 4 is a rear elevational view thereof.

I claim:

The ornamental design for a saddle rack, substantially as shown.
